UNITED STATES PATENT OFFICE.

JOHN M. JANESONE, OF RICHMOND HILL, NEW YORK.

AEROPLANE.

1,031,797.

Specification of Letters Patent.

Patented July 9, 1912.

Application filed October 30, 1906. Serial No. 341,250.

To all whom it may concern:

Be it known that I, JOHN M. JANESONE, a citizen of the United States, and a resident of Richmond Hill, in the county of 5 Queens and State of New York, with post-office address 403 Welling street, have invented certain new and useful Improvements in Aeroplanes, of which the following is a specification.

10 My invention relates to aerial propulsion apparatus in which an aeroplane is employed for its sustaining effect and is combined with a propeller for giving a forward motion.

15 The object of my invention is, among other things, to provide means whereby the apparatus may be started from the surface of the earth, and in any position where the ground or a prepared way will permit suitable vehicle wheels to travel.

20 Another object is to combine with the aeroplane a propeller of such character that it shall have an ascensional as well as a propulsive action, its ascensional action assisting that of the aeroplane as soon as the aeroplane has acquired sufficient forward movement.

25 Another object is to provide suitable means for directing the flight of the machine.

30 Briefly stated, my invention consists broadly of an aeroplane, a frame or body sustained thereby and suitable road wheel or wheels carried by said frame and an air propeller mounted on the road wheels, the object being to provide for sustaining the apparatus upon the surface of the earth and propelling the same forward by contact with the earth assisted by the action of the 35 air propeller until the aeroplane acquires the necessary ascensional power after which the apparatus rises taking with it the road wheels and the motive appliances geared to said road wheels and air propeller.

40 My invention consists further in the combination of an aeroplane, a road wheel or wheels, a motor mounted on a frame sustained from the aeroplane and an air propeller also carried by said frame for giving an ascensional effect assisting the aeroplane and a propulsive effect in the air after the road wheels leave contact with the earth.

45 My invention consists also in details of construction and combinations of parts as hereinafter more particularly described and claimed.

Figure 1 is a side elevation of a form of apparatus embodying my invention. Fig. 2 is a vertical section through one of the road wheels and propellers. Fig. 3 shows one of the vanes or paddles detached from the propeller wheel. Fig. 4 is a section through the hub of a propeller wheel. Fig. 5 is an end view of the apparatus. Fig. 6 is a longitudinal section through the frame or body of the vehicle. Fig. 7 is a cross section of the same on a line just forward of the motor.

50 The frame of the aeroplane comprises the outside longitudinal ribs or bars 1 joined by the curved end bars 2 to the central longitudinal bar 3 made preferably of an angle piece of aluminum. Stretched on said frame to form the wing surface are sheets 4 of any suitable material as for instance 55 aluminium properly secured to the frame and constructed as above in the manner set forth. An intermediate curved frame 2' 60 may be used to insure greater rigidity. The cross pieces 2, 2' are curved as shown 65 to produce a double concave aeroplane which, by its form or shape, will have greater stability against dipping sidewise, the body of the apparatus being sustained 70 from the central rib 3 in any suitable 75 manner.

75 The body or frame of the vehicle may be of any desired form and supported from the aeroplane by the depending arms 5 in either or both of which are interposed the turn 80 buckles 6 or other means for varying the length of the arms and thereby varying the 85 inclination of the aeroplane to determine the angle of ascension.

80 7 is a body or frame sustained from the 90 arms or hangers 5. The body 7 may be of any suitable shape, although shown as of 95 cigar shape and carries a suitable motor, preferably a gasoline engine of any form indicated at 8. The engine is sustained on 100 a bed 9 fixed in the body 7 or otherwise 105 suitably mounted and within convenient reach of the operator whose seat is indicated at 10. Projecting from the frame or body 7 at opposite sides are the hollow axle 11 through which extend the axle or axles 11' provided with the propulsion road wheels, the rims of which are indicated at 110 12. These propulsion wheels are adapted to travel upon any surface either prepared surface of an ordinary roadway or, if desired, upon tracks during the forward

movement in acquiring ascensional power. I prefer, however, to so construct them that they may travel upon any ordinary roadway, thus insuring a suitable forward movement of the apparatus upon said roadway until the conditions may warrant the ascensional powers being brought into play by proper adjustment of speed, angle of inclination of an aeroplane, ascensional power of 5 the air propeller or other adjustments made 10 at the will of the operator.

The air propeller is embodied in and forms a part of the road wheels which thereby become propulsion wheels operating by 15 frictional contact with the earth and by the effect of the vanes or paddles in said wheels upon the air. The air propeller is a paddle wheel having blades mounted to pivotally turn on axes parallel to the axis of rotation 20 of the wheel itself. The manner of construction of this part of the apparatus is as follows: Fixed to axle 11' is a drum or cylinder 13 to which are attached the radially extending rectangular frames 14, the side 25 arms of which afford means for pivotally mounting the transverse blades 15 of the propeller. The axle 11', as will be understood, is driven through suitable intervening mechanism of any desired character, not 30 shown, from the motor 8 thus causing a revolution of the drum of cylinder 13 with the attached frames 14, said frames 14 carrying the rim 12, forming the rim of the road wheel. Fixed to the hollow shaft 11 is an 35 eccentric 16.

17 is the eccentric strap or sleeve from which radiate arms 18. The latter in turn impart movement through links 19 to rods 20 connected to arms or brackets 21 secured to the pivoted vanes 15. By this means the set of vanes or paddles in each frame 14 is caused to turn so that the faces of the vanes 40 will be presented at different angles to the body of air through which they are forced 45 by the action of the motor 8. The effect is substantially a feathering effect, but the adjustment of the cam and of the mechanism is such as to produce a feathering effect suitable for permitting the paddle wheel to 50 exert a lifting and a forward propulsive effect as will be readily understood from inspection of Fig. 2 in which the direction of revolution of the wheel is indicated by the arrow.

55 As will be seen, during their downward movement on the forward side of the wheel, the vanes are in a position to exert a lifting effect and as they pass around toward and slightly past the vertical line through the 60 center of revolution of the wheel they act with a propulsive effect, but during their upward and forward movement they are turned so as to move edgewise through the air and present but small surfaces for action. 65 This feathering operation may obviously be

secured by other mechanisms, although the form of mechanism described is, as will be seen, of great simplicity.

In addition to the appliances already described, a suitable trailing or steering wheel 22 is provided which is adapted to travel on any supporting surface until ascensional power is acquired. Said trailing wheel also may form a third wheel adapted to properly support the apparatus and prevent it from turning on the axis of the main shaft 11. The trailer wheel 22 is fastened to the stern post or steering post 23 suitably mounted in a framework and having a proper steering wheel 24 in reach of the operator. A steering vane 25 is also provided. This vane has both horizontal and vertical surfaces as indicated and is mounted on a stem 26 carried by a post 27. The latter is adapted to turn in a horizontal plane to vary the presentation of the vertical surfaces of the vane to the atmosphere thereby permitting the apparatus to be steered horizontally. The stem 26 for the vane is properly mounted on the post so that it may be turned in a vertical plane thereby varying the presentation of the horizontal surfaces of the vane and permitting the apparatus to be steered vertically.

To assist in directing the apparatus, the 95 axle or shaft 11 may be made in two parts connected independently of one another with the motor through suitable clutches and reversing gears whereby one wheel may be propelled alone or their directions of revolution may be reversed with reference to one another, by suitably operating the handles 28 of such clutch and reversing gear to permit the engine shaft to run free of one shaft 11 or the other as desired or to reverse 105 the movement of one or the other shaft as desired.

The general operation of the apparatus would be briefly as follows: Placed upon any roadway or in any position in which 110 the wheels 12 may be sustained upon the surface of the earth a forward movement is given by the engine 8 operating through the propeller wheels as in any self-propelled road vehicle. This forward movement, 115 when the air propeller is combined with said wheels, in the manner described, is assisted in a measure by the vanes of the paddle wheel which also act to give ascensional force assisting the ascensional effect of the 120 aeroplane. The vehicle then moves forward, being partially sustained by the ascensional effects exerted on the air and partly by the road wheels 12, the proportion of the weight sustained by the latter gradually decreasing with the ascensional effects in the air until finally the apparatus will rise free of the ground, carrying with it the 125 whole propulsive apparatus employed either upon the surface of the earth or in the air. 130

When sustained in the air, the lifting or sustaining effect is the combined effect of the aeroplane, and the vanes of the propeller moving in a downward direction and the 5 propulsive effect is due to the forward propulsive action of said vanes already described, thus causing the apparatus to move forward through the air. By adjustment of the lifting effect, as, for instance, by varying 10 the inclination of the aeroplane, the apparatus may be caused to move over the surface of the earth with the wheels 12 just clear thereof or, by suitable increase of speed, the apparatus may be caused to move 15 at higher levels. When it sinks to the surface to bring the wheels 12 in engagement then the propulsion takes place through frictional engagement of the rims with the surface and the apparatus can thereby acquire 20 a positive forward motion again at a sufficient rate to cause it to ascend and clear the ground again. The office of the steering wheel or lever 24 has already been described. The vane 25 obviously is called into play 25 when the apparatus is in flight and may, if desired, be adjusted to cause it to lift just enough to clear the ground or to bring it back to the surface in order to acquire additional forward propulsive effort. The 30 initial ascensional power of the aeroplane can be determined by adjusting the turn buckles 6 or other devices in order to produce ascension or to vary the angle of ascension.

35 What I claim as my invention is:

1. The combination, substantially as described, of an aeroplane, a frame or body sustained therefrom, a vehicle wheel supporting the frame or body and aeroplane, 40 a driving motor connected to said wheel, and an air propeller having a series of vanes mounted in suitable axes carried by said wheel and adapted to act on the air in the manner described on their downward and 45 rearward movement to tend to raise the machine as well as to assist the wheel and mounted so as to be entirely within the periphery of the wheel which rests upon the ground in propelling the machine forward, 50 and means for feathering said vanes whereby after the machine rises from the ground the vanes will operate on the air to drive the machine forward as well as to assist the aeroplane in sustaining the machine during 55 such forward movement.

2. The combination of an aeroplane, a frame or body sustained therefrom, a vehicle wheel or wheels supporting the frame, and an air propeller and lifting device comprising 60 paddles carried by said wheel or wheels, said paddles being mounted entirely within the supporting rim of said wheels and turning on axes parallel to the axis of rotation of said wheels, said paddles being 65 provided with feathering devices adapted to

feather the paddles so as to cause them to act on the air on their downward and rearward movement so as to drive the aeroplane forward and to also produce a lifting effect directly and independently of the aeroplane 70 but which will supplement that of the aeroplane due to its own forward movement and a motor geared to said vehicle wheel, as and for the purpose described.

3. The combination of an aeroplane, a 75 frame or body sustained thereby, a motor carried by the frame, a paddle wheel air propeller mounted on an axle extending transversely from said frame or body and having its paddles arranged to turn on axes parallel to the axis of rotation of the propeller and mounted within the body of the paddle wheel to support the paddles entirely within the rim, an eccentric drum or cylinder carried by a hollow shaft projecting from the frame or body and having said axle extending through it, and an eccentric strap having radiating arms connected to the paddles.

4. The combination of an aeroplane, a 80 frame sustained thereby; an eccentric drum or cylinder mounted on a hollow shaft extending from the frame, a drum or cylinder fixed to an axle extending horizontally from said frame and through said eccentric drum, 85 paddle supporting frames extending radially from the axle supported drum or cylinder and provided with paddles adapted to turn on axes parallel to the revolution of said drum, and an eccentric strap connected to said paddles through arms radiating therefrom and links joined to arms secured to the vanes or paddles.

5. The combination of an aeroplane, a 90 frame or body sustained therefrom, hollow shafts extending transversely from the frame, driving axles extending through said hollow shafts and provided with drums or cylinders mounted on the outer ends thereof, a series of radially projecting frames 95 forming the body or framework of a road wheel and having a rim adapted to travel on a roadway, paddles mounted in said frames and pivoted on axes parallel to the axis of the wheel and an eccentric mounted 100 on the hollow shaft and having an eccentric strap connected to the vanes or paddles as described so as to produce a lifting and propulsive effect, thereby, in addition to the forward and ascensional effect, producing 105 rotation of the road wheel on the surface of the earth and an accompanying forward motion of the aeroplane.

6. The combination of an aeroplane, road 110 wheels, an air propeller embodied in said 115 wheels and located entirely within the supporting rim of said wheels and a motor geared to said road wheels whereby the power of the motor applied to the wheels 120 may be expended in a lifting effect pro- 125

duced in the aeroplane during the movement forward by the adhesion of the road wheels combined with the propulsion effect of the air propellers mounted in said wheels.

5 7. The combination with an aeroplane and supporting wheels therefor provided with rims whereby they may travel upon a roadway, of means for driving said wheels to force the plane forward by adhesion of
10 said supporting wheels, and an air propeller embodied in said wheels for continuing to

drive the plane forward after a velocity has been attained by adhesion sufficient to cause the plane to lift the wheels from the ground.

Signed at New York in the county of 15
New York and State of New York this 29th
day of October A. D. 1906.
